UNITED STATES PATENT OFFICE.

ALFRED T. STIMSON, OF EUREKA, CALIFORNIA.

MACHINE FOR JOINTING AND SHAPING SHINGLES.

SPECIFICATION forming part of Letters Patent No. 368,117, dated August 9, 1887.

Application filed October 15, 1886. Serial No. 216,334. (No model.)

To all whom it may concern:

Be it known that I, ALFRED T. STIMSON, of Eureka, in the county of Humboldt and State of California, have invented a new and Improved Machine for Jointing and Shaping Shingles, of which the following is a full, clear, and exact description.

My invention relates to shingle-machines, and has for its object to take the shingles as they leave the shingle-saw, bunch them radially in the machine, ornament the ends thereof in any desired fashion, and simultaneously joint their upper longitudinal edge.

The invention consists in the construction and combination of the several parts, as will be hereinafter fully set forth, and pointed out in the claims.

Reference is to be had to the accompanying drawings, forming a part of this specification, in which similar letters of reference indicate corresponding parts in all the figures.

Figure 1 is a plan view of the machine, and Fig. 2 is a front elevation thereof. Fig. 3 is an elevation from the inner side of the machine, as indicated by the line *xx* in Fig. 1. Fig. 4 is a plan view of a shingle as it leaves the shingle-saw, the dotted lines showing the amount of jointing to be done; and Fig. 5 illustrates the form of the shingle after leaving my machine when knives of the form shown are employed.

In the construction of my shingle-machine I employ two horizontal parallel frames, 1 and 2, supported upon suitable legs, 3, a proper distance apart.

Upon the upper frame, 1, near the forward end thereof, a rotary table, 3, is pivoted, consisting of concentric circular plates 4 and 5, made integral with vertical horizontally-projecting arms 6, which arms radiate equidistance apart from the center of said table to a point beyond the outer circular plate, 4, forming thereby six or more V-shaped compartments, 7, of equal size, adapted to receive the shingles 8, as will be hereinafter set forth.

The pivotal pin 9 of the rotary table 3 is journaled at the top in one end of a horizontal bar, 10, which, extending above said table, is usually curved outwardly and downwardly to an attachment at its lower vertical end with one of the supporting-legs 3. The said curved

bar 10 is provided with an integral apertured vertical offset, 11, near its engagement with the pivotal pin 9 of the table, adapted to form a bearing for the forward end of a rectangular horizontal cutter-head, 13, carrying longitudinally of the same cutter-bars 14. The said cutter-head is made to extend rearward, slightly elevated above the radial arms 6 of the table 3, to find a bearing at its rear end in a projection, 15, formed upon the forward vertical arm of a U-bar, 16, which bar, having the said arm secured to a rear transverse brace, 17, of the upper frame, 1, is arched in a right line to the rear, its other vertical arm being secured at the back of said frame. The shaft of the horizontal cutter-head 13 is provided with a pulley, 12, upon the rear end thereof.

Between the upper and lower frames, 1 and 2, at the forward end of the machine, a vertical shaft, 18, is journaled, carrying a pulley, 19, and a pinion, 20, above said pulley. A slight distance to the rear of said shaft 18 a second vertical shaft, 21, is journaled in the same manner as the aforesaid shaft 18, with the exception that shaft 21 extends through the upper frame, 1, having keyed thereon at that point a pinion, 22, and between the frames a toothed wheel, 23, connection between the two shafts being had through a train of gearing, 24. The said train of gearing may consist of any ordinary combination to reduce speed, as the object thereof is simply to effect a reduction from the rapid motion of the pulley 19 and transmit slow motion to the pinion 22 of shaft 21, which said pinion 22 is adapted to mesh with a geared feed-wheel, 25, secured to the under side of the inner circular plate, 5, of the table 3. In this manner a steady continuous slow rotary movement is imparted to the said table.

A semicircular guide-plate, 26, is attached centrally to the front of the upper frame, 1, from whence it extends, partially encircling the rotary table 3, at an elevation above the same about one-half the height of the radial arms 6 thereon, to a position to the rear of the forward arm of the U-bar 16. The purpose of this guide-bar is to keep the shingles in proper alignment when placed in the compartments 7, as shown in Fig. 1.

Within the vertical arms of the U-bar 16

horizontal shafts 27 and 28 are journaled, the shaft 27 upon a plane with the top of the upper frame, 1, and the shaft 28 above the same.

The lower horizontal shaft, 27, is provided with a pulley, 29, keyed thereon outside the rear vertical arm of the said U-bar, while upon the other end, outside the forward vertical arm of the bar 16, a cutter-head, 30, is detachably secured thereto, which cutter-head 10 may be of any desired shape, that shown in the drawings being more or less triangular, and a similar cutter-head, 31, is adapted to be likewise secured to the forward projecting end of the upper longitudinal shaft, 28, the two cutter-heads 15 being positioned parallel, as the one is purposed to act in conjunction with the other. Each of the said cutter-heads is so positioned 20 as that when the knives are secured thereto the ends of the shingles clamped in the compartments of the rotary table will be roughed thereby into any shape required, according to the form of knife used. The aforesaid upper shaft, 28, is provided with a pulley, 32, keyed thereto within the U-bar 16.

25 A vertical shaft, 33, is journaled in proper bearings, 34, secured to the rear transverse brace, 17, of the upper frame, 1, and the corresponding parallel brace of the lower frame, 2. Between the said bearings a pulley, 35, is keyed to the shaft, and to the upper portion extending above the bearings two cutter-heads, 36, are secured one above the other, adapted to receive the cutter bars or blades 37. The said cutter-blades finish the edge of the 35 shingles after having passed through the independent roughing cutter heads and knives 30 and 31, and are therefore of more or less similar shape to the aforesaid roughing-heads.

The form of cutter heads and blades may be 40 varied to produce any configuration of edge required by the operator with little trouble and in a short space of time.

The various pulleys mentioned in connection with the machine are adapted to be rotated by the independent lines of belting 41, 42, 43, 44, and 45, which run over larger pulleys, 46 47 48 49, and the extreme front small pulley, 50, which is in line with pulley 19 of the vertical shaft 18, through which motion is 50 conveyed to the rotary table. The said pulleys are usually mounted upon a shaft, 51, extending longitudinally parallel with one side of said machine, which shaft receives motion usually through a drive-pulley, 53, mounted 55 on the end thereof.

The upper roughing cutter-head is rotated by means of the belt 42, passing over pulleys 47 and 32, the lower roughing-cutter through belt 41, passing over pulleys 46 and 29, and the 60 finishing-cutters receive motion through cross-belt 44, engaging pulleys 49 and 35, while the upper horizontal cutter is revolved by the belt 43, running over pulleys 48 and 12. All the cutters are turned at a high rate of speed, the 65 table only revolving with a slow motion.

In the operation of my machine, a pattern, 52, representing the form in which the shin-

gles are to be cut is detachably clamped or bolted to the face of one or more of the radial arms 6, the jointed longitudinal edge bearing 70 upon the circular plates of the table and the fancy-cut edge thereof extending outward, slightly bearing against the semicircular guide 26. The pattern is now brought in registry with the cutter-heads and the cutter 75 knives or bars thereon are adjusted to said pattern and secured in position upon the heads for work. The shingles are now packed in the compartments 7 of the rotary table just as they leave the shingle-saw—that is, with one longitudinal edge jointed and the ends squared, as shown in Fig. 4. When the shingles have been packed in said compartments with their jointed edge bearing upon the table, as shown in Fig. 1, the machine is put in motion and the 80 table, revolving from left to right with a slow motion, carries the shingles nearly in contact with the guide 26, which serves to give them a uniform contour, and, leaving said guide, the 85 said bunched shingles are brought in contact with the independent cutters 30 and 31, which 90 cutters roughly shape the ends to conform with the pattern. As the table revolves farther around, the rotating horizontal cutter suspended above said table joints the upper ends, 95 left unjointed by the saw, and finally the shingles are carried by the table between the cutters 36, where they are finished smoothly. When a compartment containing finished shingles is 100 brought in front of the operator, who stands at the cut-away portion of the frame, (shown in Fig. 1,) the said operator removes the completed shingles therefrom and substitutes therefor others uncut. The finished shingle, as cut by the 105 pattern shown in the drawings, is illustrated in Fig. 5. Upon a machine constructed as above described any desired shape may be imparted to the end of a shingle.

Having thus described my invention, what I claim as new, and desire to secure by Letters Patent, is—

1. The combination, with a frame carrying cutters and having a rotary table pivoted thereon, and provided with radial arms, of a semicircular guide-bar attached to said frame and partially surrounding said table, said guide-bar having one end disposed to permit of the close approach thereto of the arms, while its other end is distant from said arms, substantially as shown and described, and for the purpose herein set forth.

2. The combination, with a frame having pivoted thereon a rotary table, 3, provided with radial arms, and a guide-bar, 26, partially surrounding said table and having one end disposed to permit of the close approach thereto of said arms, while its other end is distant from said arms, of the cutter-heads 30 and 31, attached to independent horizontal shafts 27 and 28 to the rear of said table, the cutter-heads 36, secured to the vertical shaft 33 at one side of and in the same horizontal plane with the said cutter-heads 30 and 31, the said cutter-heads adapted to have knives

secured thereto, and means for revolving said table and cutter-heads, substantially as shown and described.

3. The combination, with a frame having a rotary table, 3, pivoted thereon, provided with radial arms, and a guide-bar, 26, partially surrounding said table and having one end disposed to permit of the close approach thereto of said arms, while its other end is distant from said arms, of the cutter-head 13, held in bearings horizontally above said table and adapted to carry knives 14, and means for revolving said table and cutter-heads, substantially as shown and described.

15 4. The combination, with a frame having a rotary table, 3, pivoted thereon, provided with radial arms, and a guide-bar, 26, partially surrounding said table and having

one end disposed to permit of the close approach thereto of said arms, while its other 20 end is distant from said arms, of the cutter-heads 30 and 31, attached to the independent horizontal shafts 27 and 28 to the rear of said table, the cutter-heads 36, secured to the vertical shaft 33 at one side of and in the 25 same horizontal plane with said cutter-heads 30 and 31, the rectangular cutter-head 13, journaled horizontally above said table, said cutter-heads adapted to carry knives, and means for rotating said table and said cutter-heads at different speed from the same shaft, substantially as shown and described.
